UNITED STATES PATENT OFFICE.

WILLIAM WALKER, OF SUMMIT, NEW JERSEY.

DESIGN FOR A TOOL.

SPECIFICATION forming part of Design No. 29,832, dated December 20, 1898.

Application filed August 12, 1898. Serial No. 688,455. Term of patent 14 years.

To all whom it may concern:

Be it known that I, WILLIAM WALKER, a citizen of the United States, residing at Summit, Union county, New Jersey, have invented 5 a certain new and original Design for a Tool, of which the following is a full, clear, and exact description.

My invention relates to a new and original design for a tool, and the same will be found 10 illustrated by the accompanying drawings, in which—

Figure 1 is a perspective view. Fig. 2 is a section taken on the line 2 2 of Fig. 1. Fig. 15 3 is a section taken on the line 3 3 of Fig. 1. As shown in the drawings, the leading features of my design consist of an elongated flat body portion. One end of this elongated body is narrowed by beveled corners. The 20 somewhat cylindrical form. In this enlarged end an opening appears, one edge of which

is beveled. One of the longer edges of the elongated body portion is also beveled, and a series of lines arranged parallel and equidistant from each other appear on said beveled face. The opposite edge of said elongated body portion contains transverse depressions closely adjacent each other. In Fig. 2 the beveled inner edge of the opening through the body portion is clearly shown, as is also 25 30 the beveled outer edge of the body portion. This same beveled edge is also indicated in a section of Fig. 3.

What I claim is—

The design for a tool substantially as herein 35 shown and described.

Signed at New York city this 1st day of July, 1898.

WILLIAM WALKER.
